Motorola, Inc., a corporation of Illinois

Application November 13, 1946, Serial No. 134,745

Term of patent 14 years

(Cl. D14—6)

To all whom it may concern:

Be it known that I, Jean O. Reinecke, a citizen of the United States, residing at Oak Park, in the county of Cook and State of Illinois, have invented a new, original, and ornamental Design for an Automobile Heater Casing or the like, of which the following is a specification, reference being had to the accompanying drawing, forming a part thereof in which:

Fig. 1 is a perspective view of an automobile heater casing, showing my new design; and

Fig. 2 is a front elevation of the heater.

The back of the casing (not shown) is substantially plain.

I claim:

The ornamental design for an automobile heater casing or the like, substantially as shown and described.

JEAN O. REINECKE.
